US00D825605S

(12) **United States Design Patent** (10) **Patent No.:** **US D825,605 S**
(45) **Date of Patent:** **** Aug. 14, 2018**

(54) **DISPLAY SCREEN OR PORTION THEREOF
WITH GRAPHICAL USER INTERFACE**

(71) Applicant: **SAP SE**, Walldorf (DE)

(72) Inventors: **Florian Jann**, Heidelberg (DE);
Michael Krenkler, Wiesloch (DE);
Emil Voutta, Heidelberg (DE); **Marc
Ziegler**, Mauer (DE)

(73) Assignee: **SAP SE**, Walldorf (DE)

(**) Term: **15 Years**

(21) Appl. No.: **29/613,182**

(22) Filed: **Aug. 8, 2017**

Related U.S. Application Data

(63) Continuation of application No. 29/539,986, filed on Sep. 18, 2015.

(51) **LOC (11) Cl.** **14-04**

(52) **U.S. Cl.**

USPC **D14/486**

(58) **Field of Classification Search**

USPC D14/485-488

CPC . G06F 3/0482; G06F 3/04842; H04N 21/478;
G06Q 30/02; G06Q 50/22; G06Q 10/06;
G06Q 50/24

See application file for complete search history.

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
